UNITED STATES PATENT OFFICE.

THOMAS LEEMING, RICHARD RAY, AND FRANCIS G. LYNDE, OF MANCHESTER,
COUNTY OF LANCASTER, ENGLAND.

MACHINE FOR BRONZING OR OTHERWISE ORNAMENTING PAPER, &c.

SPECIFICATION forming part of Letters Patent No. 258,309, dated May 23, 1882.

Application filed March 8, 1882. (No model.) Patented in England January 4, 1873, No. 46, and October 27, 1874, No. 3,704, and in Germany September 21, 1877, No. 439.

To all whom it may concern:

Be it known that we, THOMAS LEEMING, RICHARD RAY, and FRANCIS GASCOIGNE LYNDE, subjects of the Queen of Great Britain, residing at Manchester, in the county of Lancaster, England, have invented a new and useful Machine for Bronzing or otherwise Ornamenting Paper or other Material, (for which we have obtained Letters Patent in Great Britain, No. 3,704, dated 27th October, 1874, sealed 9th April, 1875; No. 46, dated 4th January, 1873, sealed 18th March, 1873, and in Germany No. 489, dated 21st September, 1877,) of which the following is a specification.

This invention relates to the construction of an improved machine for bronzing or otherwise ornamenting paper or other material, and is represented in the accompanying drawings, in which—

Figure 1 is a longitudinal section of the machine; Fig. 2, a sectional plan, and Fig. 3 a cross-section, of the same.

Similar letters in all the figures represent similar parts.

The improved machine is constructed of a box or case, A, provided with a table, a, formed with a guide, b, and adjusted to an opening in the front of the box or case, the said opening being provided with a flap-valve, c, for the purpose hereinafter described.

d is a hopper suspended within the box or case by means of india-rubber springs e, so as to allow of a jerking motion being communicated to it by kickers f, operated by ratchet-wheels g, an adjustable buffer, o, being provided for each kicker.

h is an india-rubber traveling table, and j and l are cross sweeping bands. k is a revolving roller, covered with plush or other suitable material; n, adjustable table for regulating the pressure of the roller k; m, outlet-opening for the paper; q, bristle-brush on the shaft of the ratchet-wheel g; p, drawer forming the bottom of the machine.

The operation of the improved machine is

as follows: The paper, after it is printed, and either in sheets or continuous rolls, is laid face side upward on the table a, with one edge against the guide b. It is then pushed forward, and as it enters the machine it passes through the flap-valve c, which prevents the bronze-dust or other powder issuing from the machine. The hopper d, containing the bronze or other powder, suspended by india-rubber springs e, as hereinbefore described, is jerked about by the kickers f, whereby the powder is shed onto the paper through wire-gauze in the bottom of the hopper as the paper passes beneath it. The kickers are actuated by the ratchet-wheels g, and a buffer, o, is provided for each kicker to beat against, the buffers being adjustable, so as to allow of regulating the discharge of bronze or other powder. The india-rubber traveling table h carries the paper forward under the cross sweeping band j, which spreads the powder on the paper and removes what is superfluous. The table then carries the paper under the roller k, which is caused to revolve by means of suitable gearing, and thoroughly works the bronze-powder into the ink, and the table n, being capable of adjustment, allows of the pressure of the roller k on the paper being regulated. The paper is then carried under the cross sweeping band l, which cleans the loose dust from the surface. It is then delivered out of the machine through the opening in the case at m, which may also be provided with a flap-valve, if required. The bristle-brush q on the shaft of the ratchet-wheels g removes any dust that may adhere to the india-rubber table. The drawer p, which forms the bottom of the machine, catches the bronze as it is swept off the paper, and this bronze is emptied into the hopper from time to time. Suitable weight-rollers are provided to keep the paper in its proper position as it passes through the machine.

Having thus described our said invention and the manner of performing the same, what we claim is—

1. In a bronzing-machine, the endless traveling table *h*, made of india-rubber or other suitable material, in combination with the cross sweeping bands *j* and *l*, as and for the purpose specified.

2. In a bronzing-machine, the cross sweeping bands *j* and *l*, operating as and for the purposes specified.

3. In a bronzing-machine, the combination, 10 with a suspended hopper, of kickers, whereby a jerking motion is imparted to the hopper for shedding the powder onto the paper, and of buffers for regulating the supply of the powder, all substantially as set forth.

15 4. The combination, in a bronzing-machine, of a suspended hopper, operated as described, buffers for regulating the supply of powder, an endless table, *h*, cross sweeping band *j* and *l*, and flap-valve *c*, these parts being arranged and

operating in the manner and for the purposes 20 described.

THOS. LEEMING.

RICHD. RAY.

FRANCIS GASCOIGNE LYNDE.
